UNITED STATES PATENT OFFICE.

ANDREW RIERSEN, OF CHICAGO, ILLINOIS.

IRONING-TABLE.

SPECIFICATION forming part of Letters Patent No. 400,009, dated March 19, 1889.

Application filed April 2, 1888. Serial No. 269,364. (Model.)

To all whom it may concern:

Be it known that I, ANDREW RIERSEN, a citizen of the United States, and a resident of Chicago, in the county of Cook and State of Illinois, have invented a new and useful Improvement in Ironing-Tables, of which the following is a specification, reference being had to the accompanying drawings illustrating the invention, in which—

- 10 Figure 1 is a side elevation of my improved ironing-table; Fig. 2, an inverted view thereof with legs closed. Fig. 3 represents a portion of the extension-brace, which protrudes beyond the leg-frame when the legs are closed.
- 15 Fig. 4 shows the construction whereby one bar of the extension-brace is made to run in the other bar. Fig. 5 shows the position of the protruding end of the brace as it is when the legs are vertically under the table.
- 20 This invention relates to an ironing-table having such a novel construction of legs and braces that the table-top hinged to one set of legs may be conveniently elevated at one end for placing a garment thereon, and at the same
- 25 time the table is suitably supported, and the legs and supports connected therewith may be folded in the most compact form.

A represents an ordinary ironing-board, which is recessed at the under side, as shown 30 at z, Fig. 2, and dotted lines z, Fig. 1, to receive the braces which support the legs when the latter are closed.

B B represent one set of legs, to which the table-top A is pivoted at II, and which are connected by a strong cross-piece, P, and by a box, W, the latter being provided with a sliding cover for storing small ironing appliances. The other set of legs, for supporting the opposite end of the table-top A, are shown at C C, 35 and they are connected by three cross-pieces, P Q U, and the cross-piece U is provided with a lip, a, on one edge, which enters a recess, b, of a cleat, J, on the board A, and is thus held in place, when the legs of the table are closed, 40 by means of a spring-bar, L, which is held to press against the cross-piece U by means of a supporting-cleat, K, secured to the under side of the table-top A. The bar L is provided with two arms, M, which slide in corresponding 45 apertures in the cleat K, and coil-springs are mounted upon said arms, bearing against the cleat and bar, which tends to throw the

bar L forward. When the table is in position for use, the cross-bar U simply lies between the cleat J and spring-bar L. A small brace, 55 D, is hinged to the lower portion of box W, and a like brace D is hinged to the cross-bar Q, and they extend, respectively, into the larger braces, G G, which are made hollow for that purpose. Spring-catches N N, properly constructed in the hollow braces G near their inner ends, enter holes in the small braces, to lock both set of braces when the table is in position for use, as shown at Fig. 1. By means of the small braces entering the larger ones, as 60 stated, a portion of the length of each compound brace D G is shortened when folding the legs. Further, to manipulate the braces so that the legs may be folded, as shown at Fig. 2, metal rods H H are attached to the 65 larger brace portions G, so that their main portions shall lie far enough from the braces for staples R freely to slide. These staples are firmly inserted in the cross-bars P P, respectively, so as to slide on said rods H. When 70 the table is in position for use, the ends of the braces G G bear on the notched parts S of the bars P, as shown more clearly at Fig. 5; but when the legs C B are being shut together the braces G G slide past the bars P; but they 75 are held by the rods H and staples R, so as properly to come back to the position shown at Fig. 5 when the legs are set under the table, as at Fig. 1. The braces G are enlarged 80 at their inner ends to receive coil-springs F, Fig. 4, which are mounted on catch-pins N, which pass through said enlarged parts and engage notches in the smaller braces, D D, to hold them rigid to the hollow braces G when the table is in the position shown at Fig. 1. 85 Said catch-pins are to be released from the braces D D when the table is to be folded. A hook and staple, g f, may be employed to make a rigid connection of the two set of braces where they cross each other when the table is 90 to be held very firmly set for ironing. When the ironing-board A is to be held rigid to the supporting-frame, a button, T, Figs. 1 and 2, is to be turned under cross-bar U, and a staple and hook may be employed to hold the 95 legs when shut to the table. By the construction detailed the braces shut into the recess formed in the under side of the table and the legs lie flat against the table, whereby the de-

vice takes up, when not in use, the least possible space. In practice it is desirable that the braces, hinges, and trimmings be of metal to attain suitable strength.

5 I claim as new and desire to secure by Letters Patent—

1. The legs B, provided with the box W and cross-bar P, and the legs C, provided with the cross-bars Q and P, in combination with 10 the small braces D, hinged to the box W and cross-bar Q, and the large hollow braces G, each of which is provided with a rod, H, each of said bars P being provided with a notch to receive the end of a hollow brace, and a staple 15 for the reception and retention of a rod, H, substantially as and for the purpose set forth.

2. The recessed table-top A, provided with the cleats K J, the latter provided with the recess b, in combination with the spring-pressed bar L, the legs C, connected by the 20 bars P Q U, the latter provided with the lip a, the braces D and G, the braces G having rods H, and the legs B, having box W and cross-bar P, the cross-bar P on each set of legs having a staple, R, substantially as and 25 for the purpose specified.

ANDREW RIERSEN.
